(57) **CLAIM**

The ornamental design for a wind operated tree-shaped Christmas display, as shown and described.

DESCRIPTION

FIG. 1 is an isometric view of a first embodiment of a wind operated tree-shaped Christmas display, showing my new design;

FIG. 2 is a front view thereof, the right side, left side, and back views are identical thereto;

FIG. 3 is a top plan view thereof;

FIG. 4 is a bottom plan view thereof;

FIG. 5 is an isometric view of a second embodiment of a wind operated tree-shaped Christmas display, showing my new design;

FIG. 6 is a front view thereof, the right side, left side, and back views are identical thereto;

FIG. 7 is a top plan view thereof; and,

FIG. 8 is a bottom plan view thereof.

1 Claim, 8 Drawing Sheets
